FIG. 4.

UNITED STATES PATENT OFFICE

BENJAMIN L. FRY, OF ST. LOUIS, MISSOURI, ASSIGNOR TO NATIONAL SALES MACHINE COMPANY, OF ST. LOUIS, MISSOURI, A CORPORATION OF MISSOURI

VENDING MACHINE

Application filed January 16, 1930. Serial No. 421,295.

This invention relates to vending machines of the type disclosed in an application filed by me November 18, 1929, Serial No. 408,082, in which there is provided a column of compartments each compartment adapted to receive one package to be sold and a vertically movable closure operates in front of the column to close all the compartments and successively uncover them as sales are to be made. The present invention relates more particularly to the means for controlling the action of the closure, the object being to provide means whereby a sale cannot be completed until the plunger has made a complete forward and backward stroke. The invention also has for its object the provision of a simple, compact and inexpensive guide and support for the plunger by which the rearward movement of the same will be limited. These stated objects, and other objects which will incidentally appear in the course of the following description, are attained in such mechanism as is illustrated in the accompanying drawings, and the invention resides in certain novel features which will be particularly defined in the appended claims.

In the drawings:

Figure 1 is a side elevation, partly in section, of so much of a vending machine as is necessary to an understanding of the present invention.

Fig. 2 is a vertical section on the line 2—2 of Fig. 1.

Fig. 3 is a horizontal section on the line 3—3 of Fig. 1.

Fig. 4 is a horizontal section on the line 4—4 of Fig. 1.

Fig. 5 is a transverse detail section on the line 5—5 of Fig. 1.

Fig. 6 is a detail perspective view of the plunger support and guide, and

Figs. 7, 8 and 9 are detail elevations illustrating the successive movements of the closure and the means for operating the same.

In the drawings, the reference numeral 1 indicates a portion of a cabinet which encloses the operating mechanism and the articles which are to be vended. At 2 is shown one column of compartments in which arti-

cles to be vended are placed, said column containing compartments 3 of proper dimensions to receive the particular package or article which is to be vended. It will be understood that the cabinet may be constructed in any desired size to contain any desired number of columns and that adjoining columns will be separated by partitions so that each column will be entirely independent of all the other columns, the partitions being omitted in the accompanying drawings. The columns and the operating mechanism associated therewith are duplicates and a description of one will suffice for a description of all. The column of compartments is preferably formed from sheet metal providing a back wall 4 and side walls 5, the front of the column being open and having outturned flanges 6, as clearly shown in Figs. 3 and 4. A door or vertically slidable closure 7 extends the full height of the column and rests against the front faces of the flanges 6, said door or sliding plate being provided with a reentrant flange 8 along one edge which fits around the adjacent flange 6 of the column so as to be guided and held thereby. At the opposite side, the plate has a rearwardly extending flange 9 which extends past the adjacent flange 6 and has a cleat or guide strip 10 secured thereto at the rear of the flange so as to engage behind the same and guide the closure in its movements. On its outer side, the flange or lip 9 is provided with a plurality of studs or projections 11 which are spaced apart distances corresponding to the heights of the several compartments in the column, the purpose of which will hereinafter appear. Secured to the framework of the cabinet at the front of the closure are bars or vertical strips 12 which cover the side edges of the closure and thereby effectually frustrate attempts to pry the closure from its guides and thereby obtain unauthorized access to the article containing compartments. Adjacent the upper extremity of the door or closure is a forwardly projecting lip or finger-piece 13 whereby the door may be drawn upwardly into its initial position after the several compartments have been filled with merchandise.

Immediately in advance of the columns of

compartments, the cabinet is formed with a shelf 14 projecting forwardly from the compartments and in said shelf immediately in front of each column is formed a coin slot 15 through which coins of the proper denomination may be inserted to effect release of a desired article. The several coin slots are so disposed that a coin inserted therein will drop at once into a coin chute 16 which will 10 guide the coin to an operating plunger 17 and which is provided with means whereby slugs, improper coins or other spurious devices will be ejected, the ejected device being placed upon a trough 18 and thence directed 15 into a hopper 19 in the lower portion of the cabinet while the good coins will be delivered into another hopper 20 disposed at the rear of the hopper 19 and separated therefrom by a partition 21. These hoppers extend from 20 side to side of the cabinet so that all the deposited coins will be received by the hoppers and directed into separate boxes or other receptacles in which they will collect until removed by the owner or custodian of the machine. The particular construction of the coin chute is immaterial in the present case, and, therefore, a detailed description and illustration of the same is unnecessary.

In the operation of the machine, the closure 30 7 is moved downwardly with a step by step movement so as to successively uncover the compartments in the column to which it is fitted. On one edge of the door or closure, at the upper end thereof and extending vertically, there is a fin 22 which projects laterally from the door or closure behind the adjacent guard strip 12 and is tapered downwardly, as shown in Fig. 2. Immediately below the shelf 14, there is a transverse angle bar 23 which provides a support for some of the parts and also braces the cabinet. Pivoted upon this cross bar 23 is a valve or stop plate 24 which extends forwardly from the bar and is of such form and dimensions that it may extend across the area of the coin slot 15 below the same and thereby prevent the insertion of a coin when the associated column is empty. The valve or stop plate is provided with a depending lug 25 disposed eccentric 45 to its pivot and a spring 26 is attached to said lug and to some adjacent fixed part of the structure so that its tendency is to swing the valve into a position away from the coin slot 15 and out of the path of an inserted coin. 50 The valve is also constructed with a tooth 26' which projects rearwardly from the pivot into the path of the fin 22, as shown in Fig. 4, so that, when the closure approaches the lower limit of its movement and uncovers the lowermost compartment, the stop plate will be rocked so as to be projected across the coin slot 15. When the closure is restored to its initial position, the spring 26 at once swings the valve away from the coin slot.

65 Below the column, an angle bar 27 extends

across the cabinet and to said angle bar, adjacent the side of the column, is secured an upstanding guide plate 28 having a vertical slot 29 therein through which is fitted a slide bar 30. Said slide bar extends forwardly 70 and passes through a vertical slot 31 in a front guide bracket 32 which is secured upon a cross bar 33 in the cabinet in advance of the column and over the hopper. On that side of the slide which is presented to the column, there is secured a bracket or plate 34 having an upper edge curved, as shown at 35, downwardly and forwardly, and also secured upon the same side of the slide is a block or cam 36 having its under edge curved, as shown at 37, to correspond to the curvature of the edge 35 of the plate or block 34 so that a passageway is provided for the several studs or projections 11 in the operation of the machine. The plate or bracket 34 has its upper portion 75 extended above the slide and projected forward to define a hook or tongue 38 overhanging the cam block 36, as clearly shown. The upper edge of the cam block 36 is recessed, as shown at 39, and pivoted upon the side of the slide immediately over the front extremity of the block 36 is a dog 40 comprising a rearwardly extending arm 41 properly shaped to rest within the recess 39 of the cam block 36, as shown clearly in Fig. 7, and having a 80 depending stop 42 at the front end of said arm adapted to impinge against the front extremity of the cam block 36, and an upstanding lug or shoulder 43 on its upper edge which cooperates with the projections 11, as 85 will be presently more particularly set forth. An expansion spring 44 is seated in a socket 45 formed in the base of the recess 39 and bears against the dog 40 so as to tend constantly to lift the arm 41 into the position 90 shown in Figs. 8 and 9. The front extremity of the slide 30 projects forwardly beyond the guide 32 and has secured thereto a laterally projecting arm 46 which is adapted to be locked to the operating plunger 17 so that 95 when the plunger is moved back and forth the slide will follow its movements. In the particular structure illustrated, the inner end of the arm 46 extends through a longitudinal slot 47 in the plunger and is provided with a 100 notch or slot 48 through which a locking pin or key 49 may be inserted to be engaged through an opening provided therefor in the plunger, as will be understood. The guide 32 is an integral part of a bracket which is 105 secured upon the cross bar 33 and rises from the front edge of the base plate 50 of said bracket, the base plate being secured upon the cross bar by a screw or rivet in an obvious manner. At the outer end of the base plate 50, a vertical web or standard 51 rises therefrom and at the rear edge of this web 51, near the upper end of the same, is an outwardly projecting lug 52 to which is attached the 110 rear end of a contractile spring 53 which has 115

its front end attached to a post 54 integral with and rising from the outer end of the arm 46, it being seen at once that the tendency of this spring is to hold the slide in its retracted position. Inasmuch as the arm 46 is normally locked to the plunger, the plunger is also normally held in its retracted position. Extending rearwardly from the edge of the guide 32 remote from the slot 31 is a web or wall 55 which extends rearwardly beyond the base plate 50 and the cross bar 33 and is turned laterally to provide a stop plate 56 against which the rear end of the plunger will normally abut, as shown most clearly in Fig. 3. By referring to Fig. 6, it will be noted that the guide 32, the web or wall 55, the web or standard 51 and the base plate 50 may be easily stamped from a single blank of sheet metal thereby expediting the manufacture and reducing the cost as well as facilitating the placing of the structure in position in a cabinet. The guide 32 is, of course, provided with an opening 57 through which the plunger may pass and by which it is guided, the plunger being further guided by an opening 58 in the front wall of the cabinet, as shown in Fig. 3.

The plunger is spaced from the web 51 a distance sufficient to accommodate a coin of the proper size and the coin, indicated at 59, will be held against falling by the plunger and the web 51 and will rest upon and against studs 151 on the inner side of the web 51, as will be understood upon reference to Figs. 3 and 5.

Pivotedly mounted within the slot 47 of the plunger is a dog 60 which has one end normally projecting forwardly and beyond the side of the plunger in such position that, when the plunger is drawn forward, said end of the dog will impinge against the web 32 and, consequently, prevent the plunger being drawn forwardly a full stroke to actuate the closure and expose a merchandise containing compartment. The opposite end of the dog projects from the slot 47 in such position that, if a proper coin has been inserted, it will ride against the edge of the coin and the dog will be thereby rocked so that its front end will clear the web 32 and be disposed within the plunger to pass through the opening 57 therewith and permit delivery of the merchandise. A spring 61 attached to the dog and to the plunger at the rear of the dog holds it normally in the web-engaging position, shown in Fig. 3. The plunger has a limited movement which will permit the dog to rock and clear the guide web 32 without binding against said web, and it will be understood that as the plunger is drawn forward the dog will be held in position entirely housed within the plunger by riding against the face of the coin until the front end of the dog has cleared the web or guard 32, whereupon the coin will be released and will roll off its support into the hopper.

It will be observed, of course, that when the sliding plate or closure 7 is raised, so as to cover the column of compartments, the contents of the compartments will not be visible but a sample of the articles disposed in each column is exposed in front of the column and for that purpose there is provided a cover 62 which is hinged to the front edge of the shelf 14 and extends downwardly therefrom to rest upon the front wall of the cabinet. In front of each column, an opening 63 is formed in this cover and below said opening a box 64 is secured to contain a sample, indicated at 65, of the goods provided in the associated column. The box may conveniently be stamped from sheet metal and formed with flanges bearing against the under side of the cover to be secured thereto by screws, indicated at 66, while the walls or sides of the box are shaped to form shoulders 67 supporting a pane 68 of transparent material close against the under side of the cover and extending entirely across the opening 63. It will thus be possible for a prospective customer to observe exactly what packages are offered for sale without being able to surreptitiously remove a package. The cover 62 may be locked in its closed position, and when it is free and raised provides access to the operating mechanism so that any stoppage of the same may be remedied and also the parts may be manipulated to permit restocking of the column.

Assuming that a proper coin has been deposited and the plunger drawn forward, as has been described, so that the coin will be released to drop into the hopper and a full movement of the plunger has been effected, it will be seen that the slide 30 has also been drawn forwardly to its full extent. Normally one of the studs 11 rests upon the dog 40, as shown in Fig. 1 and in Fig. 7. When the slide 30 moves forwardly, the dog is drawn from under this stud which is then caused to rest upon the upper edge of the cam block 36, the door or closure 7 remaining in its upper position. As the slide moves forwardly so as to bring the block 36 under the stud or projection, the dog 40 will be rocked into the position shown in Figs. 8 and 9 by the spring 44 and any attempt to push the plunger back will then be frustrated by the engagement of the upraised end of the arm 41 impinging against the stud, so that the customer is compelled to impart a full forward stroke to the plunger. As the slide continues its forward movement, the hook 38 will be carried over the engaged stud 11, as shown in Fig. 8, and, consequently, the plate or door 7 cannot then be raised and efforts to shake the machine for the purpose of obtaining two articles for one coin will prove abortive. As the plunger completes its forward stroke, the stud 11 will be alined with the cam passage between the block 34 and

the cam block 36 and the door or sliding plate 7 may then descend to the extent permitted by the engagement of the stud with the curved surface 35. The door will not, however, make a full down movement to entirely uncover a compartment until the slide has been retracted to permit the stud or projection 11 to pass from the curved passage but as soon as the slide has been retracted so as to carry the front end of the block 34 from under the stud, the stud may drop and, of course, the sliding door or plate 7 will drop to uncover the compartment. The door, however, cannot drop so far as to uncover a second compartment inasmuch as when the first stud 11 clears the block 34 a second stud will be brought into the position shown in Fig. 7 resting upon the upper edge of the dog 40. The retraction of the plunger and the slide is, of course, caused by the contraction of the spring 53 which was put under tension when the plunger was drawn forward. The rearward movement of the plunger and the slide is limited by the impact of the rear end of the plunger against the stop plate 56, as has been stated and as will be understood. Upon referring to Fig. 1, it will be noted that when the plunger and slide are thus retracted the studs 11 will be in a vertical plane spaced rearwardly from the shoulder 43 of the dog 40 and when the door has been lowered so as to uncover all the compartments in the column the studs below the uppermost stud will be below the front end of the block 34 so that upward movement of the door would be prevented by contact of the studs with the slide, although the stud will readily clear the block in the opening movement of the door. When it is necessary to restock a column of compartments, the cover 62 is raised and the locking pin or key 49 withdrawn, whereupon the spring 53 will be further contracted and an additional rearward movement will be imparted to the slide. This movement, if not limited, would carry the dog 40 rearwardly beyond the studs or projections 11 so that the door 7 would drop to the bottom of the cabinet but the stop shoulder 43 will impinge against the stud and thereby limit the rearward movement of the slide, as will be understood upon reference to Fig. 1. After the compartments have been filled, the operator by an upward lift imparted to the fingerpiece 13 may raise the door 7 and the dog, being thus relieved of the weight of the door will swing to the position shown in Figs. 8 and 9 and the slide will be further retracted so that the block 34 will be carried beyond the plane of the several studs or projections and the dog 40 likewise carried beyond said plane to permit the door or closure 7 to be raised to the top of the column, the further retracting movement of the slide being arrested by impact of the upstanding post 54 against the guide 32. The fingerpiece 13 should project

forwardly to such a distance that if the cover 62 be swung upwardly against the guards 12, said fingerpiece will project over the upper edge of the cover and thereby support the door while the slide is being again moved forward manually to permit the reinsertion of the locking key 49. When this key has been reinserted, the parts will be all restored to their initial positions and the door will then be supported in its fully raised position by the dog 40 and the parts will be ready for a second series of sales.

Having thus described the invention, I claim:

1. In a vending machine, the combination of a column of article-containing compartments, a closure slidably mounted at the front of the column to extend across all the compartments, spaced projections on one edge of the closure, a slide mounted below the column at one side of the closure, cam blocks on the slide defining a return passage for a projection on the closure, one of said blocks having an overhanging arm to extend over the entrance end of the passage above the projection and prevent upward release of the projection from said passage, and means on the slide to prevent a reverse movement thereof to move said overhanging element from over the projection.

2. In a vending machine, the combination with a column of article-containing compartments, a closure extending across all the compartments to cover the same, and spaced projections on one edge of the closure, of a slide at the side of the closure having cam blocks presented to the closure and defining an arcuate passage to receive one of said projections whereby a forward and then a rearward movement of the slide will effect downward movement of the closure to uncover a compartment, a dog mounted on the slide at the entrance end of said passage, and means whereby after a projection has entered the passage the dog will engage behind the projection to prevent its relative return movement.

3. In a vending machine, the combination of a column of article-containing compartments, a closure for the fronts of all the compartments, spaced projections on one edge of the closure, a slide at the side of the closure, cam blocks on the slide defining a sinuous passage for the successive projections on the closure whereby a forward and then a backward movement of the slide will effect downward movement of the closure to uncover a compartment, a dog pivoted on the slide at the entrance end of said passage, one of the projections on the closure normally resting on said dog, and a stop lug at the front end of the dog to arrest rearward movement of the slide.

4. In a vending machine, the combination of a column of article-containing compart-

ments, a closure for the front ends of all the compartments, a series of projections on one edge of the closure, a slide having cam blocks thereon defining an arcuate passage for the successive projections whereby a forward movement of the slide followed by a reverse movement thereof will effect downward movement of the closure to uncover a compartment, a dog pivoted on the slide and normally supporting one of the projections, an operating plunger, a detachable connection between the plunger and the slide, yieldable means for retracting the slide, the dog being provided with a stop shoulder at its front end normally resisting rearward movement of the slide by engagement with the supported projection, and means for rocking the dog whereby when the closure is lifted the slide may be fully retracted and the closure fully raised.

20 In testimony whereof I affix my signature.
